UNITED STATES PATENT OFFICE

132,851

DESIGN FOR A HAIRPIN TRAY OR THE LIKE

Carla B. Cooper, Los Angeles, Calif.

Application August 2, 1941, Serial No. 102,653

Term of patent 3½ years

To all whom it may concern:

Be it known that I, Carla B. Cooper, a citizen of the United States and a resident of the city of Los Angeles, in the county of Los Angeles and State of California, have invented a new, original, and ornamental Design for a Hairpin Tray or the like, of which the following is a specification, reference being had to the accompanying drawing, forming part thereof.

In the drawing:

I claim:

The ornamental design for a hairpin tray or the like, substantially as shown.

CARLA B. COOPER,
